UNITED STATES PATENT OFFICE

BROR WITI, OF SKOYEN, NEAR OSLO, NORWAY

SKI TIE.

Application filed March 16, 1929, Serial No. 347,517, and in Norway March 29, 1928.

The present invention relates to ski ties of the type which have toe irons that are secured to the upper side of the ski, one of the said toe irons being provided with a projection or projections which engage into a slot or cut-out portion or portions in the other toe iron.

It is the object of my invention to provide a ski tie of the above mentioned type which may be easily and accurately positioned and secured in adjusted position on the ski.

In the drawing Figs. 1 and 2 illustrate two different embodiments of a ski tie according to my invention in plan view.

Fig. 3 shows a section along the line III—III in Fig. 2 and

Fig. 4 shows a detail in perspective.

In the drawing 1 is a portion of the ski proper, and 2 and 3 designates the toe irons, which are secured to the ski 1 by means of securing screws 4.

According to Fig. 1 the toe iron 3 is provided with a projection 5 which extends into a cut-out 6 in the other toe iron 2 in such manner that an opening is formed between one side edge 7 of the projection 5 and the side edge 8 of the cut-out, both of which edges 7 and 8 respectively are bevelled as indicated in Fig. 1. Said opening preferably extends in a direction at right angles to the longitudinal direction of the ski 1 and receives an adjusting screw 9 as described more fully below. The other side edge 10 of the projection 5 engages the side edge 11 of the portion 12 of the toe iron 2 which forms the foremost limit of the cut-out 6. In order that the toe irons may be relatively turned somewhat during the adjusting operation, said edge 10 is arcuated, as shown. The portion 12 is relatively narrow and by means of a slot 19 it may be given relatively great length in order to become somewhat resilient in the longitudinal direction of the ski.

In Fig. 2 is illustrated an embodiment in which both toe irons 2 and 3 are provided with a projection 13, between the adjacent bevelled side edges 13' of which the adjusting screw 9 is received.

Between that side edge of each of the projections which is not engaged by the screw 9

and the adjacent side edge of the cut-out in the other toe iron may be placed narrow intermediate members about which the toe irons may be turned somewhat when the toe irons are adjusted in position upon the ski. As indicated in Figs. 2 and 4 said intermediate members may be formed by the upwardly bent ends 14 of a member 16 which is placed below the projections 13 and sunk into the upper surface of the ski. The member 16 then at its middle portion is provided with an opening 15 through which the screw 9 is passed.

Instead of using the said intermediate members the side edges of each of the projections might also be rounded and engage the edge of the cut-out, in a way similar to that indicated at 10, 11, 12 in Fig. 1.

As indicated in the sectional view in Fig. 3 the horizontal portions of the toe irons may be slightly arched or curved, preferably in the longitudinal direction of the ski.

When the toe irons are to be mounted and adjusted upon a ski, the point where the screw 9 is to be placed is at first marked upon the ski, and said screw 9 is then screwed into the ski to a suitable depth. Then the toe irons are passed with their edges 7 or 13 respectively in under the head of the screw 9 and the latter is tightened somewhat more, so that it presses the toe irons against the ski with a suitable pressure, due to the resiliency of the horizontal portions of the toe irons.

Thus the toe irons are temporarily secured, and they may now be accurately adjusted in the desired positions on the ski, both as regards the distance between the vertical portions of the toe irons and the inclination thereof in relation to the longitudinal direction of the ski. During such adjustment the adjusting screw 9 will cause sufficient friction between the toe irons and the ski, so that the toe irons will not be displaced. When the toe irons have been accurately adjusted in the desired position the securing screws 4 are inserted and tightened, so that the horizontal, arched portions of the toe irons are pressed entirely down on to the surface of the ski.

Having now particularly described and

ascertained the nature of my said invention and in what manner the same is to be performed, I declare that what I claim is:

1. Toe irons for a ski tie comprising horizontal portions adapted to be secured to the upper surface of the ski, one of which portions is provided with a projection received by a cut-out in the other portion, one side edge of the projection and the adjacent side edge of the cut-out being beveled, such side edges being so far apart that a slot is formed therebetween, an adjusting screw entering the slot and acting against the beveled portions of said edges and forcing the opposite edge of the projection against the adjacent side edge of the cut-out and thereby temporarily securing said portions to each other and to the ski under the adjustment of said irons.
2. Toe irons for a ski tie comprising horizontal portions adapted to be secured to the upper surface of the ski, each portion being provided with a projection and a cut-out adapted to receive the projection of the other portion in such manner that a slot for an adjusting screw is formed between adjacent edges of the projections, said edges being beveled in order that the adjusting screw may act against said beveled edges and force the opposite edges of said projections against the adjacent edges of the cut-outs and thereby temporarily securing said portions to each other and to the ski under the adjustment of said irons.
3. A toe iron as claimed in claim 1, in which the portion of the toe iron limiting the cut-out is resilient in the longitudinal direction of the ski.
4. A toe iron as claimed in claim 2, in which the portion of the toe iron limiting the cut-out is resilient in the longitudinal direction of the ski.
5. A toe iron as claimed in claim 1, having a narrow portion limiting the cut-out at one side thereof, said portion being extended by the arrangement of a slot extending sidewise in the horizontal portion of the toe iron.
6. Toe irons, as claimed in claim 1, in which the side edge of the projection which engages one side edge of the cut-out is curved.

BROR WITH.
